UNITED STATES PATENT OFFICE.

WILLIAM W. DICKINSON, JR., OF LITTLE ROCK, ARKANSAS.

APPARATUS FOR BURNING BRICK.

1,355,821.

Specification of Letters Patent. Patented Oct. 19, 1920.

Application filed February 6, 1919. Serial No. 275,329.

To all whom it may concern:

Be it known that I, WILLIAM W. DICKINSON, Jr., a citizen of the United States, residing at Little Rock, in the county of Pulaski and State of Arkansas, have invented a certain new and useful Improvement in Apparatus for Burning Brick, of which the following is a full, clear, and exact description, reference being had to the accompanying drawings.

This invention relates to the burning of brick and has for its general object the provision of new and simplified apparatus for the performance of such burning whereby the amount of permanent construction is decreased, whereby heat is conserved, and whereby the employment of inclosed structures is avoided thus permitting the building and demolition of the kiln by means of labor-saving transporting devices. More specifically, the present invention is for certain improvements in detail over the devices and apparatus illustrated in my earlier application filed March 18, 1918, Serial No. 223,026; the provision of a construction of kilns such that no above ground permanent construction is employed and the below ground construction much reduced, and entirely removed from underneath the kiln; while further objects and advantages of the invention will become apparent as the description proceeds.

In the drawings accompanying and forming a part of this application, I have shown the preferred embodiment of my said invention, although it will be understood that this drawing is illustrative merely and does not limit me to the details of construction therein shown. In these drawings Figure 1 represents a top plan view of a series of kilns and their adjuncts embodying my improvements; Fig. 2 represents a side elevation of the same kilns together with the kiln-shed and showing the kilns in different states of completion; Fig. 3 is a sectional view corresponding to the line 3—3 of Fig. 1; Fig. 4 is a top plan view of the kilns shown in Fig. 3, portions of the same being broken away to different levels to illustrate the interior arrangement; Figs. 5 and 6 are transverse sectional views on the lines 5—5 and 6—6 of Fig. 1, respectively; and Fig. 7 is a perspective view of one of the draft-hole covers.

The general construction employed in the present apparatus is substantially the same

as that shown in my application of March 18, 1918, Serial No. 223,026, namely: that I build a large number of kilns in a row, adjacent kilns being separated by a narrow 60 passageway defined between impervious transverse walls, and said passageway communicating in each case with the upper part of the kiln on the one side while being completely out of communication with the kiln 65 upon its opposite side. Each kiln is formed with eyes or arches at the bottom for the entrance of the heating agent, and is covered over at the top to prevent the direct escape of combustion products; and means 70 are provided whereby the narrow passageway leading from each kiln may be put into communication with the eyes or arches of the next succeeding kiln, other means being provided for creating a draft from the 75 terminal kiln. In the drawings, A, B, C, D, E, * * * X, Y, Z, represent the kilns which are here shown as bounded at the sides by vertical parallel walls 1, 1 of previously burned brick and lined interiorly 80 with a layer 2, 2 of unburned carbon-containing brick. Connecting these walls are the transverse walls 3^a, 3^b, 4^a, 4^b, 5^a, 5^b, etc., dividing the space between the walls 1, 1 into rectangular compartments, the wall 3^b 85 being separated from the wall 4^a, the wall 4^b from the wall 5^a, etc., so as to produce the passageways a, b, c, etc., heretofore mentioned. These transverse walls are preferably made of unburned brick and the end 90 walls of the kiln are generally covered with a layer or outside course of burned brick as shown at 6. Each of the transverse walls 3^b, 4^b, 5^b, etc., terminates at a point below the top of the remaining walls so that the 95 passageways a, b, c, etc., communicate with the kiln chambers A, B, C, etc., respectively.

Inside the chambers thus formed the bricks to be burned are piled in the usual well-known manner, leaving the customary 100 eyes or arches 7, 7 which run from side to side of the kiln and register with similar openings in the side walls 1, 1. I have also shown the passageway a as loosely piled with unburned brick, the better to prevent 105 buckling of the walls thereof under the influence of the heat, but this is not necessary in all cases. In any event, the bottom part of this passageway ought to be left open and unobstructed. This may be done by forming 110 therein an arch or eye just as was done in the body of the kiln; but another mode

which I have used with much success is to bridge the passageway from point to point with elongated fire brick 8, 8 upon which the unburned bricks are laid. I have also had very good success in laying such fire brick near the top of the passageways as shown at 8^a in Fig. 3 (either with or without other fire brick ties in the lower part of the passageway) and building the unburned 10 bricks only to or into the upper end of such passageway. These are minor refinements and subordinate to my present invention, it being only essential that each wall of a pair should be shorter than the other wall so 15 that the passageway may communicate with one of the kiln-chambers and not with the other, the lower end of each passageway opening through the exterior wall 1 by means of an aperture 9.

20 The top of the entire kiln-structure is covered with a platting 10 of previously burned bricks which is held in place by the unburned bricks below; and I have found it advantageous, as explained in my former 25 application, to make the topmost courses of the kiln out of carbon-containing brick, since the burning of the outer layers is thereby facilitated.

For the purpose of conveying the heated 30 gases and combustion products from one kiln to the next I have illustrated the use of movable conduits, preferably consisting of elongated metal casings 12, 12 each having at one end the deflected portion 13 adapted 35 to communicate with one of the openings 9, and the body thereof being formed with spaced apertures 14 adapted to register with the eyes or arches 7, 7 of the succeeding kiln, communication being established by means 40 of sheet metal thimbles 15, 15. The interior of each of the casings is lined with fire brick or other refractory material as shown at 16, and the portion of the eyes or arches not occupied by the thimbles 15 is filled with a 45 rubble wall 17. I have shown the casings 12 as encircled by hoops 18 provided with eyes 19 adapted for the reception of suitable falls whereby the devices may be moved along the kilns as necessity requires, but it 50 will be clear that other means, such as cars, rollers, or the like could be employed.

Any desired number of these casings can be employed in connection with a single kiln row, and different classes and qualities of 55 brick will frequently require different treatment. In the usual condition I prefer to connect only three kilns in series, using for the purpose two of these casings on each side as shown in Figs. 1 and 2. In this case 60 fire is applied only to the first kiln of the series, the products of combustion being conveyed to the second kiln for warming and preheating, and thence to the third kiln for drying, after which the moist air is conveyed 65 to the exhaust; but a larger or smaller num-

ber of kilns could be connected in the series within my invention if found necessary and desirable.

For the creation of the necessary draft any suitable or desired means can be employed, 70 the simplest and most satisfactory which I have so far conceived being the provision of a pair of horizontal underground tunnels 25, 25, one outside of and parallel to each of the side walls 1, 1, said tunnels being connected together at one or both ends of the kiln row as by a transverse tunnel 26 and also provided with exhausting apparatus 27 which may be a chimney, exhaust-fan, or other equivalent. Each of these tunnels 25 80 is provided opposite each of the apertures 9 with an upwardly opening draft hole 30, adapted to receive either a cover 31 whereby it may be closed or an elbow 32 connecting it with the opening 9 with which it registers. It will be understood that immediately upon the completion of the burning of any one kiln the conduits 12 and elbows 32 are advanced one step and the heating agent applied to the next succeeding kiln 90 until all are burned; and that the different kilns in the same row may be in different stages for completion at the same time, those kilns in advance of the one which is burning being under construction and those in the 95 wake of the burning process being in process of demolition. It is feasible also to arrange kilns in circular or rectangular or other endless manner so that the burning may be truly continuous as heretofore described in my application Serial No. 223,026 above referred to.

It will be understood that numerous changes in details of construction, arrangement, manipulations and procedure can be adopted within the scope of my inventive 105 idea.

Having thus described my invention, what I claim is:—

1. In combination, a plurality of brick kilns each having its interior part of bricks 110 loosely piled and formed with eyes or arches, and having its top and sides formed of bricks closely piled, one of the sides of each kiln being formed with a vertical passageway which communicates at its upper 115 end with the interior of said kiln adjacent to its top and is formed at its lower end with an opening, and a movable conduit adapted to connect said opening with the eyes or arches of the succeeding kiln. 120

2. In combination, a plurality of brick kilns each having its interior part of bricks loosely piled and formed with eyes or arches, and having its top and sides formed of bricks closely piled, one of the sides of 125 each kiln being formed with a vertical passageway which communicates at its upper end with the interior of said kiln adjacent to its top and is formed at its lower end with an opening, a draft duct adjacent to 130

all said openings, a movable conduit adapted to connect any one of said openings with the eyes or arches of the next succeeding kiln, and a movable conduit adapted to connect any one of said openings to said draft 5 duct.

3. In combination, a plurality of brick kilns built in a row and each having eyes or arches, successive kilns being spaced apart 10 to define vertical passageways, the upper end of each passageway communicating only with the kiln at one side of itself and the lower end of each passageway having an opening, and a movable conduit member 15 adapted to connect any opening with the eyes or arches of the succeeding kiln.

4. In combination, a plurality of brick kilns built in a row and each having eyes or arches extending transversely of such 20 row, successive kilns being spaced apart longitudinally of the row to define vertical passageways, the upper end of each passageway communicating only with the kiln at one side of itself and the lower end of each 25 passageway having at each end a laterally facing opening, and movable conduit members located upon opposite sides of said row and adapted to connect said openings with the eyes or arches of the next succeeding 30 kiln.

5. In combination, a plurality of brick kilns built in a row and each having eyes or arches, successive kilns being spaced apart 35 to define vertical passageways, the upper end of each passageway communicating only with the kiln at one side of itself and the lower end of each passageway having an opening, and a movable conduit having 40 near one end an opening adapted to register with said last named opening and formed in its sides with other openings registering with the eyes or arches of the succeeding kiln.

6. In combination, a plurality of brick 45 kilns built in a row and each having eyes or arches, successive kilns being spaced apart to define vertical passageways, the upper end of each passageway communicating only with the kiln at one side of itself 50 and the lower end of each passageway having an opening, a movable conduit having near one end a mouth adapted to register with said last named opening and formed in its sides with other openings registering 55 with the eyes or arches of the succeeding kiln, and thimbles establishing communication between said eyes or arches and said last named openings.

7. In brick burning apparatus, in combination, a plurality of brick kilns each of 60 which is formed at one side with a vertical passageway whose upper end communicates with the kiln interior and whose lower end is provided with one or more openings,

tunnels for the escape of combustion products having openings adjacent said first openings, movable conduit members whereby the passageway openings of one kiln can be connected with the eyes or arches of another kiln, means for connecting to said 70 tunnel openings the openings of said other kiln, and a suction device connected with said tunnels.

8. In brick burning apparatus, in combination, a pair of spaced parallel tunnels, 75 a plurality of brick kilns built in a row and each having transverse eyes or arches, successive kilns being spaced apart to define vertical passageways, the upper end of each passageway communicating only with the 80 kiln at one side of itself and the lower end of each passageway having an opening at each end, each of said tunnels having an opening adjacent to the passageway opening, movable conduit members adapted to 85 establish communication between any passage opening and its corresponding tunnel opening, and other movable conduit members adapted to establish communication between any other passage opening and the 90 eyes or arches of the succeeding kiln.

9. In brick burning apparatus, in combination, a pair of spaced tunnels, each tunnel having a plurality of spaced apertures opening through the ground surface, 95 a row of brick kilns located between said tunnels and each having transverse eyes or arches, successive kilns being spaced apart to define passageways which register with said tunnel apertures, the end walls of 100 said passageways being apertured and the upper part of said passageways communicating with the upper part of the respective kilns, and right angular conduit members adapted to be applied to said passage openings, certain of the same having lateral openings adapted to register with the eyes or arches of the succeeding kiln and others of the same having downturned openings adapted to register with said tunnel apertures. 105

10. A conduit member for the purpose described comprising a hollow, elongated, metal casing having one end angularly turned and the other end closed, a refractory lining inside said casing and a plurality of spaced openings through the wall and lining of said casing and having their axes parallel to the axis of said laterally turned end. 115

11. A conduit member for the purpose described comprising a hollow elongated metal casing having one end angularly turned and the other end closed, a refractory lining inside said casing, and a plurality of spaced openings through the wall and lining of said casing and having their axes parallel to the axis of said laterally turned 120 end. 125

4
end, in combination with removable thimbles adapted for insertion in said last named openings.

12. In brick burning apparatus, in combination, a draft conduit, a plurality of brick kilns built in a row, along said conduit and each having eyes or arches entering the lower part and a downwardly extending passageway communicating with the upper part of each of said passageways terminating in an opening, and said draft conduit having openings near said

passageway openings, movable conduit members adapted to establish communication between any passageway opening and one of said draft conduit openings, and other movable conduit members adapted to establish communication between any other passageway opening and the eyes or arches of the succeeding kiln. 20

In testimony whereof, I hereunto affix my signature.

WILLIAM W. DICKINSON, JR.
